MULTIPLE NOZZLE GUN TYPE OIL BURNER
AND CONTROL THEREFOR

Joseph A. Logan, Hadley, Mass., assignor to Gilbert & Barker Manufacturing Company, West Springfield, Mass., a corporation of Massachusetts

Application March 3, 1947, Serial No. 731,919

5 Claims. (Cl. 158—28)

1

This invention relates to improvements in oil burners of the so-called gun type for house heating systems.

From the manufacturer's standpoint the success of his equipment in use depends to a large extent upon the skill used in installing the oil burner in the home. The installing work is customarily done by men employed by the distributors who buy from the manufacturers. Of course the manufacturers supply literature and offer training to guide the men in the field to install oil burners to the home user's advantage. Yet there are some features of the gun type burner which under to-day's routine practice cause them to operate less efficiently in the home than they can be made to operate under this invention. The object of the invention is to provide a new and improved burner of the said type, feasible to be made at the factory, distributed for installation under to-day's routine practice, and result in the user getting a burner in the home to operate with a substantial increase of efficiency as compared to prior art burners. By efficiency is meant particularly the efficiency in the burning of the oil with resulting economy in oil consumption. In some installations the invention will avoid disagreeable noise in burner operation as compared to prior art burners under the same conditions.

The structure and mode of operation of the invention is disclosed by way of example and in detail. Considerable discussion is needed to show the reason for much of the detail.

For the house heating use, it is necessary to vary the firing rate of the burner over a certain range, say from a minimum of one gallon per hour to a maximum of two and three quarters gallons per hour. The firing rate is determined by the size of atomizing nozzle used. The size of the nozzle to be used is determined by the dealer who installs the burner. The manufacturer desires to standardize on one size of burner which by merely change of nozzle size will be adequate for any firing rate within the stated range. However, as the firing rate is varied of course the rate of oil flow is varied and the rate of air flow through the air tube of the burner needs to be correspondingly varied. Using one air tube of a given size, the change of rate of air flow will result in a change in the velocity of the air supplied through the tube to the oil atomizing nozzle. Over the desired range of firing rates, the variation in air velocity is so great as to result in inefficient mixing of air and oil at certain firing rates. For example, if the air tube is proportioned to provide the proper velocity of air for efficient mixing at a high firing rate, then, when air is passed through the same size tube at a substantially less rate for low rate firing, the velocity of the air will be lowered to such an extent that there will be a substantial loss in the efficiency of

the mixing of the air and oil. However, if the air tube is proportioned to provide the proper velocity of air for efficient mixing at a low firing rate, then, when air is passed through this same tube at a substantially greater rate for high rate firing, the velocity of the air will be so high as to cause objectionably noisy combustion and possibly also to change the desired shape of the flame.

This invention has for an object to provide in 10 a burner of the described type for house heating purposes, a plurality of air tubes of different diameters, arranged one within another, and valve means to enable the air for combustion to be supplied through one or more of these tubes, according to the oil firing rate selected for the burner.

The invention finds one preferred use in connection with a burner of the type described, which is adapted to be fired at more than one rate according to the user's choice or as determined 15 automatically by a suitable control, and the invention has for a further object to provide means, whereby a change in the oil firing rate will automatically cause a change in the number of air tubes used to supply the air for combustion. 20 In this way, for two rates of oil firing, two air supply tubes may be provided suitably proportioned so as to yield approximately the same velocity of air for high rate and low rate firing.

In the accompanying drawings:

30 Fig. 1 is a side elevational view of an oil burner embodying the invention;

Fig. 2 is a cross sectional view thereof taken on the line 2—2 of Fig. 1;

Fig. 3 is a fragmentary top plan view, with parts 35 broken away to show the air inlet valve together with the manual means and the automatic means for moving it;

Fig. 4 is a sectional plan view taken on the line 4—4 of Fig. 1 and showing the dual air tube structure and the valve control therefor;

Figs. 5 and 6 are cross sectional views taken on the lines 5—5 and 6—6, respectively, of Fig. 4;

Fig. 7 is a fragmentary sectional elevational view taken on the line 7—7 of Fig. 2;

Fig. 8 is a sectional plan view taken on the line 8—8 of Fig. 6, showing the firing rate selector valve;

Fig. 9 is a fragmentary sectional view of a detail relating to the mounting of the air inlet valve;

Fig. 10 is a wiring diagram of the electrical elements and circuits of the burner;

Fig. 11 is a fragmentary sectional plan view showing a modification; and

Fig. 12 is a diagram illustrative of a modification in the control shown in Fig. 10.

Referring to these drawings, the invention will be disclosed in what is now considered its best form, in which the spray producing means is a nozzle of the oil pressure atomizing type. How-

ever, the invention is capable of use with other types of atomizing nozzles, as will be clear to those skilled in the art, and it is not intended to have the invention limited to the use of the one specific type of atomizing means shown in the drawings.

Referring first to Fig. 1, the frame of the burner includes a hollow casting, which may be supported by a pedestal 1 and which has a lower cylindrical part 2 and an upper part 3, forming a housing for a fan shown in part at 4 in Fig. 3. This fan delivers air at relatively low pressure, say a few ounces, into the rear end of the tubular passage 5 (Figs. 1 and 7), which extends through part 2 and is closed at its rear end by a cover 6. On one face of the fan housing 3 (Fig. 3) is mounted an electric motor 7, which drives the fan 4 and an oil pump 8. The pump is fixed centrally to the cross bar portion 9 of a U-shaped frame, the spaced legs 10 of which are fixed at their inner ends to the other face of fan housing 3. A casing 11 encloses the frame 9, 10 and part of pump 8 and has a plurality of air inlet openings 12. Air passes through these openings into the hollow interior of casing 11 and enters the fan housing 3 through the inlet opening 13. An adjustable shutter 14 controls this opening. The fan 4 is fixed directly to the shaft 15 of motor 7.

The pump shaft 16 is preferably driven from the motor shaft by means of a centrifugal clutch, the driving and driven elements of which are respectively indicated at 17 and 18. This clutch may be like that disclosed in my copending application Serial No. 672,106, filed May 24, 1946, and its purpose is to delay the starting of the pump until the fan has acquired considerable speed and to stop the pump before the fan. The pump may, for example, be constructed as shown in the patent to Osborne No. 2,233,709, dated March 4, 1941, and include a cut-off valve and by-pass valve located in the casing 19. The pump is arranged to draw in oil through a suction pipe 20 (Fig. 1), and force it out through a delivery pipe 21 to the burner. The cut-off valve in the casing 19 will open to allow flow from the pump to pipe 21 only after a predetermined minimum pressure, say 85 pounds per square inch, has been established. The by-pass valve opens to allow oil to by-pass to the suction side of the pump, when the pressure of the pumped oil reaches a predetermined maximum pressure, say 100 pounds per square inch.

Referring to Fig. 4, the tubular air passage 5, into the rear end of which air is delivered by fan 4, communicates with two coaxially arranged tubes 22 and 23. The outer tube 22 has a flanged end 24 which is fixed as indicated to the outlet end of the cylindrical member 2. The inner tube 23 is supported from the outer tube by two circular series of radial posts 25, each of which is riveted to both air tubes. The outer and inner tubes 22 and 23 are provided on their outlet ends with air directing cones 26 and 27, respectively.

Within the inner tube 23 are arranged the oil atomizing means of the burner. In the particular example herein shown, such means consist of two nozzles 28 and 29 (Figs. 2 and 4) of the oil pressure atomizing type. These nozzles 28 and 29 have different capacities and may, for illustration, be assumed to have the respective capacities of one and two gallons per hour. These nozzles 28 and 29 (Fig. 4) are mounted on the outer ends of pipes 30 and 31 respectively, which are mounted in spaced parallel relation and are secured at their inner ends to a casing 32, which contains a firing rate selector valve. The oil delivery pipe 21 from the pump 8 extends through a recess in cover 6

into passage 5 and is connected to the valve casing 32 as shown.

The firing rate selector valve is best shown in Fig. 8. The oil supply pipe 21 communicates with one end of an inlet passage 33 formed in casing 32. The other end of this passage connects with a cylinder 34 which is formed in casing 32 and in which the selector valve slides. This cylinder 34 has outlet passages 35 and 36 which communicate with the nozzle pipes 30 and 31, respectively. The firing rate selector valve consists of two axially-spaced discs 37 and 38, fixed to a stem 39 and slidably mounted in cylinder 34. The stem 39 passes out of casing 32 through a suitable packing 40 and a packing nut 41 and is provided with a spring 42, which presses against a collar 43 on the stem and yieldingly holds it in the low firing rate position shown. In this position, the valve disc 38 blocks off the high rate outlet 36 and the valve disc 37 uncovers the low rate outlet 35 and enables it to communicate with inlet 33. If the valve is moved to its high firing rate position, valve disc 37 will block off outlet 35 and valve disc 38 will open outlet 36 and allow it to communicate with inlet 33. A longitudinal passage 44, which extends from the outer face of one valve disc to the outer face of the other, enables oil to flow back and forth from one end of the cylinder 34 to the other and thus permits free movement of the valve.

The valve 37, 38 may be moved to its high firing rate position by means of a lever 45 pivotally mounted at 46 between ears 47 on the casing 32. One arm of lever 45 has a lateral extension 48 (see also Fig. 7) which underlies the collar 43 and is operable, when actuated by means later to be described, to raise the collar and thus the valve 37, 38. A light spring 49 connects the lever 45 to one of the ears 47 and yieldingly holds extension 48 in contact with the collar 43.

The inner air tube 23 (Fig. 4) is proportioned to pass air at a rate and velocity suitable for operation of the burner at the lower firing rate. When the burner is operated at the higher firing rate, air is supplied at an increased rate and then both air tubes 22 and 23 are used, the two enabling air to pass at the increased rate without substantially increasing the velocity. It is therefore necessary to provide means for closing and opening the entrance to the annular passage 50 between the inner and outer air tubes. Such means, as shown, consists of an annular ring 51, to opposite faces of which are fixed stampings 52 of triangular shape in cross section. The ring 51 has a diametrical part 53 (Figs. 5 and 7) to which are fastened at their inner ends two studs 54, arranged in spaced parallel relation (Fig. 7). These studs are slidably mounted in bearings 55, provided on the valve casing 32, one above and one below the latter, as shown in Figs. 6 and 7. The rear ends of the studs 54 are fixed to a cross bar 56. Springs 57, one encompassing each stud 54, are located between the part 53 and the inner ends of bearings 55 and yieldingly hold the air valve in the closed position shown. Centrally on the cross bar 56 (Figs. 4 and 8) are a pair of spaced ears 58 which receive between them the outer end of the long arm of a bell crank lever 59 (Fig. 8) and to which such arm is pivotally connected by a pin 60. Bell crank 59 is mounted between the described ears 47 adjacent lever 45 and is pivotally connected to such ears by the same pin 46. To the short arm of bell crank lever 59 (Fig. 4) is connected a link 61 which extends outside the cylinder 2 and is connected to the low-

er end of a lever 62. Lever 62 (Figs. 1 and 2) is pivotally mounted on a stud 63, which passes through the casing 11 and is fixed to one of the arms 10. Fixed to the fan housing 3, as by legs 64 (Fig. 2), is a casing 65, which contains a solenoid. The core 66 of this solenoid is connected to lever 62. When the solenoid is energized by means to be described, lever 62 will be swung counterclockwise, as viewed in Fig. 2, thus pulling link 61 outwardly and swinging lever 89 clockwise, as viewed in Figs. 4 and 8. This will pull outwardly on the studs 54 compressing springs 57 and moving the air valve 51, 52 to its open position. In such position the parts 52 of the valve serve as streamlining to guide the air around the air valve without creating undue eddies.

The described lever 45 of the firing rate selector valve is actuated by the bell crank 59 after the latter has opened the air valve to a substantial extent. A projection 67 (Fig. 8) on the bell crank engages an abutment 68 on lever 45 and moves the latter to shift the firing rate selector valve to its high rate position. Thus, the annular air space 50 between air tubes 22 and 23 is opened whenever the selector valve is shifted to cause operation of the burner at the high firing rate.

The ignition means for the burner may include the spark electrodes 69 (Fig. 4) which are supported in proper position to ignite the spray from either nozzle 28 or 29. These electrodes are fixed one in each of two insulating tubes 70, which in turn are mounted for longitudinal adjustment in a support 71, being suitably held in adjusted position as by the set screws 72. This support 71 also receives the low and high rate nozzle supply pipes 30 and 31 respectively, which pipes are suitably held to the support, as by the set screws 73 (Fig. 2) in a manner to enable longitudinal adjustment of the pipes and thus the atomizing nozzles which they carry. The support has three radially extending pins 74 (Fig. 2) the outer ends of which contact the inner peripheral wall of the inner tube 23 and centralize the support. The selector valve casing 32 also has legs 75 (Fig. 6) which support it from the cylindrical member 2. The nozzles and spark electrodes may be held in proper longitudinal position in the air tube 23 in any suitable way. For example, two rods 76 (Fig. 7) are secured at one end one to each of two ears 77 on the valve casing 32 and the other ends 78 of the rods are out turned at right angles, as at 78, and received one in each of two diametrically opposed notches formed in the rear end face of cylinder 2. The cover 6 holds the ends 78 tightly in their notches. The inner ends of these rods are threaded and secured to the casing by a pair of nuts 79, in such a way as to enable longitudinal adjustment of the casing 32 and thus of the nozzles 28 and 29 and the electrodes 69. When the cover 6 is removed, one may reach into the tube 5 and disconnect the link 61 from bell crank 59, after which the unit comprising firing rate selector valve, air valve, nozzles and ignition electrodes may be withdrawn from the rear end of cylinder 2 by pulling rearwardly on rods 76.

It has been stated that, when the firing rate selector valve is moved to its high rate position, air is supplied to the burner at an increased rate. This is accomplished by opening the shutter 14 to increase the effective area of the air inlet to fan 4. This shutter is threaded on a screw 80 (Fig. 3) and it is suitably held against rotation, as by a stud 80', fixed on cross bar 9. The shutter has a central opening large enough to clear the

driven element 18 of the centrifugal clutch. The screw 80 has an outer plain cylindrical portion, which is mounted to slide axially as well as turn in a bearing 81 in the cross bar 9 and an inner plain cylindrical portion which is also mounted to slide axially as well as turn in a bearing 82 (Fig. 9) in the fan housing 3. A spring 83 (Fig. 3) on the screw tends to hold it in the axial position shown, in which a shoulder 84 on the screw abuts the cross bar 9. Threaded on this screw, near its outer end, is an adjustable abutment, such as a nut 85, and a lock nut 86 for holding the abutment in adjusted position. On the end wall of casing 11 (Figs. 1 and 2), a lever 87 is pivoted at 88 and has one end forked to straddle screw 80 in back of nut 85. The other end of lever 87 is connected by a link 89 to the upper end of the described solenoid-actuated lever 62. When the solenoid is energized, the lever 62 will be swung counterclockwise, as viewed in Fig. 2, thus pulling on link 89 to cause lever 87 to swing clockwise, as viewed in Fig. 3, to engage nut 85 and move screw 80 axially outward and move the shutter 14 outward to increase the effective area of the inlet to fan 4. When the solenoid is deenergized, the spring 83 will move the screw 80 axially inward until the shoulder 84 abuts the cross bar 9. The extent of movement of the shutter 14 caused by energization of solenoid, depends on the position of nut 85. The amount of movement of lever 87 is always the same but the axial movement imparted to screw 80 can be varied by varying the amount of lost motion between the lever and nut 85. The high rate position of the air shutter 14 may be adjusted with precision by turning nut 85 on screw 80. The low rate position of the shutter may be adjusted with precision by turning the screw 80 which will move the shutter axially in or out as required.

The burner is arranged for intermittent operation under the control of a room thermostat switch. The electrical connections are shown conventionally in Fig. 10. The room thermostat switch 90 is arranged to close on a demand for heat from the burner and close a low voltage circuit, which is supplied from the secondary 91 of a transformer and which includes a relay coil 92, the thermostat switch 90, the secondary 91, and the wires 93, 94 and 95 that connect these elements in series. The primary 96 of this transformer is connected by wires 97 and 98 to supply wires 99 and 100, respectively. The relay coil 92, when energized, operates a switch 101 to close a circuit to the burner motor and to the ignition means. The motor circuit may be traced as follows, from supply wire 99, wire 102, switch 101, wires 103 and 104, motor 7, and wire 105 to supply wire 100. The ignition electrodes 69 are connected by two wires 106 to the secondary 107 of a suitable ignition transformer, the primary 108 of which is respectively connected by wires 109 and 110 to the wires 104 and 105 and thus in parallel with the motor so as to be energized and deenergized simultaneously therewith.

The solenoid which serves to shift the lever 62 to adapt the burner for operation at the high firing rate is shown at 111. It may be controlled automatically or manually as desired. As illustrative of the automatic control, a thermostat switch 112 is arranged in a circuit, which includes in series the solenoid 111 and relay switch 101, this circuit being traced as follows, from supply wire 99, wire 102, switch 101, wires 103 and 113, thermostat switch 112, wire 114, solenoid 111, and wire 115 back to supply wire 100. The ther-

mostat switch 112 may be responsive to outdoor temperature or to the temperature at any other location, such as will evidence a need for operation of the burner at the high rate. For example, the switch 112 may be set to close when the outdoor temperature falls to some selected value, say 20° F. Then, when the switch 101 is closed by the room thermostat on a demand for heat from the burner, the solenoid 111 will be energized to cause the rate of oil flow and the rate of air flow to be increased and the air valve 51, 52 to be opened to enable both air tubes to conduct air to the oil atomizing means. For manual operation, a push button switch 116 (Fig. 12) may be substituted for the thermostat switch 112 and connected to the wires 113 and 114, respectively, so as to open and close the circuit to the solenoid 111 in the same way that it was done by switch 112. This switch 116 may be located at any convenient point in one of the living rooms of the house and it will then enable the burner to be changed over for high rate firing without going into the cellar to reach the burner. It is, however, obvious that the change over for high rate firing may be effected by means of a hand lever (not shown) located at the burner.

In operation, the burner is started up automatically by the room thermostat 80 when there is a demand for heat. Oil will be supplied by pump 8 to nozzle 28 or 29 depending on whether the firing rate control switch 112 or 116, as the case may be, is open or closed. If this control switch is open, the burner will be operated at the low rate while if it is closed, the burner will operate at the high rate. Air will be supplied by fan 4 at a high or low rate according to whether the selector valve is set for high or low rate firing. If air is supplied at the high rate, the air valve 51, 52 will be opened by lever 59 when the selector valve and air shutter 14 are moved to high rate position. Then the two tubes 22 and 23 will be used to conduct air to the spray nozzle. If air is supplied at a low rate, the air valve 51, 52 will be closed by lever 59 when the selector valve and air shutter are moved to low rate position. Then, the inner tube 23 only will be used to conduct air to the burner. The air tube arrangement affords two air conduits of different cross sectional area, which can be proportioned so as to give the proper velocity of air at the atomizing nozzle for high and for low rate firing. As shown, one such conduit comprises the inner tube 23 alone and is used for low rate firing and the other conduit comprises both tubes and they are used for high rate firing. The air supplied from each tube will mix with the spray emitted from the nozzle 28 or 29, as the case may be, and the combustible mixture will be ignited by the electrodes 69 in the usual way. The burner will continue in operation until the demand for heat is satisfied, when the burner will be stopped by the opening of switch 101, when the room thermostat switch 90 opens. On stopping of the burner, solenoid 111 will be deenergized and the air valve 52, 53, the firing rate selector valve and air shutter 14 will be shifted back to low fire position. It is obvious, however, that these various valves need not necessarily be shifted back to low fire position when the burner stops. They might, for example, be operated manually and latched in the high rate position in the same general way as is shown in Fig. 11, hereinafter described.

The invention provides for an automatic change in the cross sectional area of the air supply conduit as the rate of oil supply is changed,

whereby the velocity of air at the nozzle may be maintained about the same for both high and low rate firing. The arrangement enables one burner to serve efficiently for all usual firing rates throughout the range normally used for house heating systems. Except for the invention, the manufacturer would have to supply burners with air tubes of different sizes, one for the relatively high firing ranges and another for the relatively low firing ranges. If a single air tube were used of the proper size to give the desired air velocity for efficient mixing of air and oil at high firing ranges, the same tube, when supplied with air at a less rate for low rate firing, would cause a decrease in air velocity so great as to result in inefficient mixing of the air and oil and poor combustion. If a single tube were used properly proportioned to give the desired air velocity for efficient mixing for low rate firing, then when the same tube is supplied with air at the greater rate needed for high rate firing the velocity of the air would be so much increased as to result in too noisy combustion and probably also in substantial change of shape of the flame. With the invention, the air velocity may be maintained within a range to secure efficient mixing for both low and high rate firing and to avoid noisy combustion.

The invention is characterized in providing for the change in area of the air conduits as the oil firing rate is changed and, in its broader aspects, is not limited to the one means herein disclosed for varying the oil firing rate. The invention is useful regardless of how the change in oil firing rate is effected.

The invention is also useful in oil burners, wherein the change in firing rate has to be effected manually by changing the size of the atomizing nozzle used. This is indicated in Fig. 11, wherein a single oil atomizing nozzle 119 and the ignition electrodes 69 are mounted in a support 120 in the inner air tube 23. This nozzle is supplied with oil through pipe 21 under pressure regulated by the usual cut-off and by-pass valves but without any other valve control. The air valve 51, 52 is mounted on studs 54 as before and these studs are slidably mounted in a support 121 in the same way that they were formerly mounted in the valve casing 32. Each of the supports 120 and 121 has supporting legs as before and the two supports are tied together by rods 122. Rods 76 are fixed at one end to the support 121 and at the other end fit in recesses in the cylinder 2 as heretofore. The support 121 pivotally supports the lever 59 which actuates the cross bar 56 to which are fixed the studs 54 of the air valve 51, 52. This lever may be manually operated from outside the cylinder 2 by pulling or pushing on a link 123. This link has a downturned end 124 which can be inserted in either of two holes 125 and 126 in an ear 127 on cylinder 2. When the end 124 is engaged in hole 125 the air valve 51, 52 will be closed for low rate firing and when such end is engaged in hole 126 the air valve will be opened for high rate firing. The burner manufacturer might supply two air tubes with each burner, one tube to be used when nozzles of relatively low firing rates are used and the other tube to be used when nozzles of relatively high firing rates are to be used. Such a plan leaves the installation of the tube and that of the oil nozzle and ignition electrodes to the dealer and the manufacturer has no assurance that the installation of these parts will be properly effected. The invention enables both tubes and all the parts supported in them, except possibly for the nozzles

themselves, to be assembled properly by the burner manufacturer leaving to the dealer only the work of screwing on a nozzle of the proper size and shifting the air valve 51, 52 by the means disclosed or other suitable means to cause one or both of the tubes to be supplied with air by the fan.

From the foregoing disclosure it will now be clear that I have provided an improved oil burner for these advantages among others. When the workman installs the improved burner for house heating, the householder will get a burner better adapted for that particular operation which will be efficient in relation to his particular househeating needs. The burner structure is better adapted for the installing workman to condition it for efficient operation under the particular conditions of the house in which it is put for use. Whereas working with prior art burners different firing rates were determined by different sized nozzles accompanied by different adjustments of air volume through the same air tube, the improved burner takes into account the increase in efficiency of different sized tubes in relation to the operation of different sized nozzles. The structure is arranged at the factory for the most convenient kind of installation work by men in the field with the result that less skill is needed in doing the installing work of putting the "mass" produced burner into that kind of operation which is highly efficient for one particular house as compared to different houses and within a substantial range. This is one of the broader aspects of the invention which is pointed out in various aspects by the following claims.

I claim:

1. In an oil burner for house heating systems, a motor, an air fan, an oil pump, a transmission for driving the fan and pump from said motor, two air tubes arranged one within the other with a passage between them, the inner tube being permanently connected to receive air from said fan, valve means operable to connect or disconnect said passage to or from the fan, oil atomizing means connected to be supplied from said pump at either a high or a low firing rate and located in the inner tube in a position such that the air from the inner tube and the air from the passage between the tubes will mix with the spray emitted from the atomizing means, means for changing the firing rate of the atomizing means from a high to low rate and vice versa, and means operable with the rate changing means for actuating said valve means to open and close the passage between said tubes when the atomizing means is adapted for high and low rate firing respectively.

2. In an oil burner for house heating systems, a motor, an air fan, an oil pump, a transmission for driving the fan and pump from the motor, two air tubes one within the other with a passage between them and connected to receive air from the fan, oil atomizing means connected to be supplied by said pump and operable at either a high or a low rate, said means being located in the inner tube in a position such that air from the inner tube and the air from the passage between the tubes will mix with the spray emitted from said means, means operable to adapt said atomizing means for high or low rate firing, and valve means operable to permit air from the fan to flow either through the inner tube or through the inner tube and the passage between the tubes to adapt the air supply to the selected rate of oil supply.

3. In an oil burner for house heating systems, a motor, an air fan, an oil pump, a transmission

for driving the fan and pump from the motor, two air tubes one within the other with a passage between them and connected to receive air from the fan, two oil conduits selectively connectible to said pump and each arranged to end with an individual atomizing nozzle located in the inner tube in such position that air from the inner tube and the air from the passage between the tubes will mix with the spray emitted from either nozzle, valve means controlling the selective connection of said oil conduits to the pump to vary the firing rate of the burner, and a second valve means operatively connected to the first valve means and operable to permit air to flow through the inner tube or the inner tube and the passage between the tubes according to the selected firing rate.

4. In an oil burner for house heating systems, a motor, an air fan, an oil pump, a transmission for driving the fan and pump from said motor, two oil conduits selectively connectible to said pump and each arranged to end with an individual atomizing nozzle, valve means to control the connection of said oil conduits to said pump to provide for a high and a low firing rate, and two air tubes arranged one within the other with a passage between them, the inner tube being permanently open and both connected to receive air from said fan, said nozzles being located in the inner air tube in such position that the air from the inner tube and the air from the passage between the tubes will mix with the spray emitted from either nozzle, and a second valve means operatively connected to the first-named valve means and operable when the first-named valve means is moved into position for low rate and high rate firing to respectively close and open the passage between said air tubes, whereby one or both of said tubes is or are connected to the fan for low and high rate firing respectively.

5. In an oil burner for house heating systems, a motor, an air fan, an oil pump, a transmission for driving the fan and pump from the motor, two air tubes arranged one within the other with a passage between them, the inner tube being permanently connected to receive air from said fan, valve means operable to connect or disconnect the passage between the tubes to or from the fan, two oil conduits selectively connectible to said pump and each arranged to end with an atomizing nozzle located in the inner air tube in such position that the air from the inner tube and air from the passage between the tubes will mix with the spray emitted from either nozzle, valve means for selectively connecting said oil conduits to said pump to provide for high and low rate firing, and means connecting the first and second valve means for opening and closing the first-named valve means when the second-named valve means is respectively positioned for high and low rate firing.

JOSEPH A. LOGAN.
